UNITED STATES PATENT OFFICE.

WILLIAM B. GORHAM, OF BOSTON, MASSACHUSETTS.

DESIGN FOR A HAND-STAMP.

Specification forming part of Design No. 5,137, dated July 25, 1871.

To all whom it may concern:

Be it known that I, WILLIAM B. GORHAM, of Boston, in the county of Suffolk and State of Massachusetts, have invented certain Improvements in Design for Hand-Stamp, of which the following is a specification:

The accompanying drawing represents a perspective view of my new design for a hand-stamp.

My design consists of a circular spindle, A, having a slightly-curved cap, B, with double torus-grooved molded edges b b. Attached to a journal formed on the lower end of the spindle A is a spring, concealed from view in a circular molded standard or socket, C, formed with an inner lip, against which the spring acts. The standard or socket C is formed on the exterior with an ovolo, D, above a cyma-reversa, E, separated by an ovolo, H, from a scotia, I, connected by an

ovolo, K, with the base of the standard or socket C, which consists of three grooved toruses, L M N. The base of the standard or socket C is formed whole, and in it is formed a slot, O, in which works a clamp, P, holding the types, the said clamp P being attached to and worked by the spindle A, which is worked up and down in the socket C.

Having thus fully described my design, what I claim is—

The design for a hand-stamp, as shown.

In testimony whereof I have signed my name to this specification in the presence of two subscribing witnesses.

WILLIAM B. GORHAM.
